US00D925964S

(12) **United States Design Patent** (10) Patent No.: **US D925,964 S**
(45) Date of Patent: **** Jul. 27, 2021**

(54) **CASSETTE STOVE**

(71) Applicant: **SENGOKU WORKS, LTD.**, Kasai (JP)

(72) Inventors: **Tadashi Sengoku**, Kasai (JP); **Takehira Sengoku**, Kasai (JP); **Akihiko Shirota**, Kasai (JP)

(73) Assignee: **SENGOKU WORKS, LTD.**, Kasai (JP)

(**) Term: **15 Years**

(21) Appl. No.: **29/707,989**

(22) Filed: **Oct. 2, 2019**

(30) **Foreign Application Priority Data**

Apr. 5, 2019 (JP) 2019-007474
